UNITED STATES PATENT OFFICE.

CORNELIUS AMBRUSTER, OF ROSLYN, PENNSYLVANIA.

INSULATING-SUPPORT FOR STORAGE BATTERIES.

1,146,298.

Specification of Letters Patent.

Patented July 13, 1915.

Application filed June 14, 1913. Serial No. 773,603.

To all whom it may concern:

Be it known that I, CORNELIUS AMBRUSTER, a citizen of the United States, and a resident of Roslyn, in the county of Montgomery and State of Pennsylvania, have invented a certain new and useful Insulating-Support for Storage Batteries, of which the following is a specification.

The principal objects of the present invention are to provide a comparatively inexpensive, strong, acid resisting and efficient insulating support which can be readily put in under and taken out from under a tank initially or in order to renew its parts and which can be adjusted to compensate for inequalities in the floor and which, when in position, has its parts properly held against accidental displacement.

Another object of the invention is to provide the parts of such material and of such form that they are adapted to do the work required of them, and that they are not subjected improperly to the stress of the load which they carry and are therefore not liable to breakage.

The invention will be claimed at the end hereof, but will be first described in connection with the embodiments of it chosen for illustration in the accompanying drawings, 30 in which—

Figure 1, is a side view of an insulating support complete, showing a portion of a tank. Fig. 2, is a sectional view of the same but showing a slight modification, and 35 Figs. 3 and 4 are perspective views illustrating details of construction.

In the drawings 1 is a pedestal of earthenware shown as flat on top. This part is made of earthenware, because it must necessarily be high enough to keep the oil 2 contained in the glass insulator 3, well above the floor, so that water, as when the floor is washed, may not reach the oil by splashing, and it is not commercially practical to 40 make a pedestal of this height that will meet all the requirements of any other material. The insulator 3 is made of glass and it could not be made of earthenware because the latter would become soaked or permeated 45 with acid or acidulated water destroying its insulating qualities. The insulator 3 is cored out or hollow as at 4.

5, is a cap as of lead alloy that is placed on top of the upper solid end of the insulator.

6, are parts of the tank.

Between the flat top of the pedestal 1 and the bottom of the insulator 3 is placed a centering piece 7, of lead or lead alloy, having three arms 8, which extend upward into the hollow core 4 of the insulator 3 and three radiating arms 9, the ends 10 of which may be bent down onto the sides of the base. By bending up one of the ends 10, it is evident that the parts 1 and 3 can be separated by a relative lateral movement. The radiating arms 9 give a three-point support so that any inequality is taken up or compensated for without putting such strains on the pedestal 1 or insulator 3 as would tend to break or chip them. Furthermore the centering piece acts as a lead pad. On top of the cap 5 and between it and the tank 6 there is placed a filling piece. This may consist of one or more leaden washers 11, which transfer the strain from the tank to the glass insulator. These washers may be dished in order to keep them stacked in central position. These washers operate as lead pads and prevent any improper transmission of the strain. If the distance to be filled by the filling piece is considerable, it would be expensive to use leaden washers, hence I provide a filling piece consisting of a porcelain disk 12 and a leaden tripod 13, the ends 14 of which are folded back onto the face of the filling piece 12 opposite to the face to which the tripod is applied, thus the ends 14 of the tripod come opposite the arms 15 thereof, so that the arms and the ends constitute a three-point support and leaden pad and thus protect the porcelain disk 12 from such strains and stresses as would break, crack, chip or otherwise injure it. Combinations of these disks 12 of different thicknesses and of the lead washers 11 can be used to make up any desired total length.

Evidently the described combination of form, material and structure produces a unitary acid resisting structure which not only 100 performs the function of insulating, but also performs the function of carrying a great load satisfactorily and efficiently, even though supported upon an uneven base or floor.

I do not claim herein the pedestal specifically, since it forms the subject of my application serially numbered 759,046.

What I claim is:

1. An insulating support for storage batteries comprising the combination of a pedestal having a flat top, an insulator having

a hollow core, a leaden centering piece having upstanding arms arranged to enter the hollow core and arms constituting pads and foldable down over the top edges of the pedestal, a cap on the insulator, and a leaden filling piece on top of the cap, substantially as described.

2. An insulating support for storage batteries comprising the combination of an earthenware pedestal having a flat top, a glass insulator having a hollow core, a leaden centering piece having upstanding arms arranged to enter the hollow core and arms constituting pads and foldable down over the top edges of the pedestal, a cap on the insulator, and a leaden filling piece on top of the cap, substantially as described.

3. An insulating support for storage bat-

teries comprising the combination of a pedestal having a flat top, an insulator having 20 a hollow core, a leaden centering piece having upstanding arms arranged to enter the hollow core and arms constituting pads and foldable down over the top edges of the pedestal, a cap on the insulator, and a filling 25 piece mounted on the top and consisting of a leaden tripod and a porcelain body embraced by the alined arms of the tripod, substantially as described.

In testimony whereof I have hereunto signed my name.

CORNELIUS AMBRUSTER.
